COMBINED CAR AND ELECTRIC COUPLER

Application filed February 28, 1927. Serial No. 171,697.

One of the difficult problems in connection with the electric railway trains is the automatic coupling of the various electrical train circuits. It is common to mount on the car couplers electric couplers for this purpose. Good metallic contact must, of course, be made between the contact pieces or terminals of two cooperating couplers, and therefore the contacts in two such couplers must be 10 yieldingly pressed together when a coupling is made. This may be accomplished by providing contacts yieldingly pressed forward so as to project beyond the transverse line of contact between two couplers, whereby the 15 contact pieces in both couplers will be pressed back when a coupling is made. It is desirable that a door or closure be provided for each electric coupler so that, when the coupler is not in use, the contacts will be housed in, 20 and thereby guard against the entrance of rain, snow or dirt into the electric coupler and against exposed live contacts or terminals that might injure workmen or others touching them. The door or closure for a 25 coupler should be automatic in its opening and closing movements, opening automatically upon the coupling together of two cars, and again closing when the cars are uncoupled. So far as I know, no one has heretofore 30 been able to provide the simple type of electric coupler, having contact pieces normally projecting forward beyond the transverse line of contact, with an automatic door; recourse being had to more complicated constructions in which the contact pieces are 35 mounted on a carrier, which moves into and out of the housing or casing of the coupler.

The object of the present invention is to provide an electric coupler of the so-called 40 stationary contact type with a door or closure and means for automatically operating the same upon the coupling and uncoupling of the cars.

In carrying out my invention, I mount an 45 electric coupler directly on a car coupler in such a manner as to be immovable thereon. The yieldingly held, so-called stationary contacts, are caused normally to project beyond the front end of the coupler, whereby they 50 will be pushed back during a coupling oper-

ation. The electric coupler is provided with a door mounted to swing from a position in front of the coupler to an idle position below the coupler. The door is preferably provided with a spring tending normally to close the 55 same. There is also provided a suitable door-opening mechanism adapted to be actuated by means on an approaching car to open the door while the electric couplers are still far enough apart to permit free swinging 60 movements of the latter. By providing a spring for closing the door, the opening means may be operated from some movable element of the car coupler itself without placing on this element any load or burden 65 except during the coupling operation, namely at a time when the energy stored up in a moving car or cars is available for operating the door or doors.

Therefore, considered in one of its aspects, 70 my invention may be said to have for its object to provide a simple and novel mechanism for operating the door or closure of an electric coupler from an element of a car coupler that has movement relatively to the coupler 75 made during coupling and uncoupling movements of the car coupler.

The various features of novelty whereby 80 my invention is characterized will herein-after be pointed out with particularity in 85 the claims; but, for a full understanding of my invention and of its objects and advantages, reference may be had to the following detailed description taken in connection with 90 the accompanying drawings, wherein:

Figure 1 is a side elevation of a car coupler of well known type having mounted thereon an electric coupler provided with a door or closure operated in accordance with the present invention, the door being shown open; Fig. 2 is a view similar to Fig. 1, showing only the electric coupler, the door being closed; Fig. 3 is a top plan view of the structure shown in Fig. 1, a portion of the car coupler being broken away, the parts being in the 95 positions corresponding to those in Fig. 1 and which they assume just before the completion of a coupling operation; Fig. 4 is a view similar to Fig. 3, showing the parts in the positions which they occupy while the coupler is 100

separated from a cooperating coupler, with the door closed; Fig. 5 is a view similar to Fig. 4, all of the parts except the door and the operating means therefor being shown 5 in section; Fig. 6 is a view similar to Fig. 2, showing the opposite side of the electric coupler from that appearing in Fig. 2 and the body of the coupler being shown in dotted lines; and Fig. 7 is a detail showing a modified connection between the rock shaft and its 10 operating bracket.

Referring to Figs. 1 to 4 of the drawings, 1 represents the head of a so-called tight-lock 15 coupler of well known construction, such as disclosed in my prior Patent No. 1,475,609 granted on November 27, 1923, having a forwardly projecting hook or nose 2 at one side, and a locking element or yoke 3 within the chamber of the head behind the open front at 20 the other side. As is well known, when two of these couplers come together, the nose or hook on one presses back the locking dog or yoke in the other; and, when the hooks have been tightly interlocked, the locking elements 25 or yoke automatically swing into their normally locking positions to prevent disengagement of the hooks from each other.

Underneath the car coupler head is fixed 30 an electric coupler head 4. In the arrangement shown, the two heads are rigidly fastened together by means of bolts 5 and 6. The details of the electric coupler are of no importance, except that there should be contact 35 pieces 7 projecting forwardly beyond the same and beyond the plane of the forward face 8 of the car coupler. These contact pieces will, of course, be spring-held in any usual or suitable way, so that they may be pressed back through engagement with cooperating contact 40 pieces when two couplers are brought together.

There is a door or closure 9 of a size and shape to fit snugly against the front end of the electric coupler in front of the contact 45 pieces. The door is provided with rearwardly extending wings 10 at its ends, that is at the sides of the electric coupler, the rear ends of these wings being pivotally connected to the casing of the electric coupler as indicated at 11, thereby permitting the door or closure to swing between an open position in which it lies underneath the electric coupler and a position in which the door fits snugly against the front end of the electric coupler, 50 preferably against a rubber or other sealing gasket, such as indicated at 12, extending around the front end of the electric coupler.

Mounted on the electric coupler, above the rear end, is a transverse rock shaft 13. On 55 each end of the rock shaft is an arm 14 projecting downward beside the electric coupler. Between each of the arms 14 and the corresponding wing of the door is a connecting rod 15. Between an upwardly projecting arm 16 on the rock shaft and a lug 17 on top

of the electric coupler, toward the front end, is arranged a compression spring 18 tending constantly to turn the rock shaft in a direction to close the door. The rock shaft has a second upwardly projecting arm 20 to which 70 is connected one end of a link 21 that extends rearwardly to and is fastened to a horizontally swinging bracket 22. The locking dog or yoke 3 of the car coupler may be operated 75 through a vertical shaft 23, having a radial arm 24 connected to a part associated with the locking dog or yoke by a link 25. On the upper end of the shaft 23 is a handle 26. The yoke swings on a vertical pin 50 and has a tail piece 51 projecting beyond the pin. 80 A spring 52 arranged between a tail on the yoke and a stationary part of the coupler head, tends constantly to hold the yoke in the position shown in Fig. 4. Normally, therefore, the yoke extends transversely across the 85 coupler head so that when another coupler head approaches in the act of coupling, the nose thereof strikes the yoke and pushes it back against the resistance of spring 51 to the point indicated in Fig. 3. Thereupon 90 the yoke slips off the end of the nose of the opposing coupler and swings back to the position indicated in Fig. 4, completing the coupling. In order to uncouple, the yoke must be swung back to the position illustrated in Fig. 3; thus leaving the nose of the 95 cooperating coupler free to be withdrawn. In this type of coupler the link 25 is not connected directly with the yoke but to a part 53 that swings about the pin 50 and plays between spaced hugs 54 and 55 on the yoke. Consequently, when the handle 26 is turned in the proper direction while the yoke is in the locking position of Fig. 4, the part 53 will travel until it strikes the lug 55, whereupon 100 the yoke will begin to swing until it reaches the release position of Fig. 3. When the yoke is brought to the position shown in Fig. 3 by the operating handle, the part 53 will, of course, still be in engagement with the lug 105 54. Fig. 3, however, illustrates not only the release position of the yoke, but also the position thereof just before a coupling is completed; the shaft 23 having been turned by means of the lug 54 acting on the part 53 and, 110 through the latter and the link 25, on the arm 24. On the operating shaft 23 is an arm or projection 27 whose free end is curved, as indicated at 28, about the axis of the operating shaft as a center. The bracket 22 has a lug 29 which, when the bracket is in the position that it occupies when the door of the 115 electric coupler is closed, and the dog or yoke 3 is in its normal idle position, lies directly in front of the arm or projection 27. When the operating handle is turned to swing the dog or yoke back, or when the hook on an opposing car coupler presses the dog or yoke back, the projection on arm 27 is swung forward, 120 pushing the projection 29 on the bracket 22 125

130

ahead of it; thereby turning the rock shaft in a direction to swing open the door. The parts are so shaped, proportioned and positioned that before the locking dog or yoke has completed its rearward swinging movement, the driving contact between the arm 27 and the projection or lug 29 will be interrupted and this lug or projection will ride on the curved face 28; thus permitting the locking dog or yoke and the operating mechanism therefor to continue their movements for a considerable distance after the door for the electric coupler has been opened, the opening of the door being completely effected before the lug or projection begins to ride on the arm 27. Figure 4 shows the relation of the parts 22 to 29 while the door is closed, whereas Figure 3 shows them in the positions that they occupy after the door has been fully opened and the locking dog or yoke fully retracted, in the act of automatic coupling. It will be seen from Figure 3 that the arm 27 serves as a stop or abutment against which the lug or projection 29 bears to prevent the spring 18 from operating the rock shaft in a direction to close the door. When the operating handle 26 is turned in the direction to unlock the car couplers, the arm 27 pushes the lever 22 forward from the position shown in Fig. 4 to that shown in Fig. 3, and serves to lock the door open until the nose of the opposing coupler has been withdrawn.

It will thus be seen that I have produced a simple and novel door operating means for an electric coupler, that will permit the use of the simplest type of coupler, namely that having the so-called stationary contacts; the door opening and closing automatically with the coupling and uncoupling of cars, being adapted to be operated manually at will through the actuating handle for the locking dog or yoke of the car coupler and requiring no application of outside energy during the closing movements.

It will be seen that the link or connecting rod 21 between the bracket 22 and the rock shaft must wobble during the operating of the mechanism. This may be provided for by making the pivot pins smaller than the openings through which they pass, or by using a link or rod such as indicated at 21A in Figure 7 and connecting the same by a ball joint 30 to the bracket and by a similar ball joint 31 to the rocker arm 20. The lug 32 on the bracket in the construction shown in Figure 7, corresponding to the lug 29 in the other figures, is shown as taking a somewhat different form although having the same functions.

While in some aspects of my invention it is not important what is the element that initiates the automatic opening of the door when two cars are coupled, it will be seen that the actuating means shown in the drawings makes it unnecessary to employ any de-

vice projecting from the car or the electric coupler for engagement with a part on an approaching car. In other words, the actuating means for the door are all in the rear, the forward part of the car coupler containing only the usual coupler features and the forward element of the electric coupler being the door. 70

While I have illustrated and described with particularity only a single preferred form of my invention, I do not desire to be limited to the exact structural details thus illustrated and described; but intend to cover all forms and arrangements which come within the definitions of my invention constituting the appended claims. 75 80

I claim:

1. In combination, a car coupler and an electric coupler fixed to the same, a door mounted for movements between a closing position in front of and an idle position beside the electric coupler, and means actuated by a part of the car coupler set in motion during the process of coupling to open said door. 90

2. In combination, a car coupler having a lock and an operating member therefor, an electric coupler fixed to the car coupler, a door mounted to swing between a position in front of the electric coupler and an idle position, and means controlled by said operating member and arranged between the same and the door to actuate the latter. 95

3. In combination, a car coupler having a locking dog adapted to be driven from a locking position to a release position by an element on an opposed car coupler during the act of coupling, an electric coupler fixed to the car coupler, a door for the electric coupler movable between closing and idle positions, and means arranged between said locking dog and said door to cause the door to open as the dog moves toward its release position. 100 105

4. In combination, a car coupler having a locking dog adapted to be driven from a locking position to a release position by an element on an opposed car coupler during the act of coupling, an electric coupler fixed to the car coupler, a door for the electric coupler movable between closing and idle positions, and means arranged between said locking dog and said door to cause the door to open as the dog moves toward its release position and while it is still a considerable distance away from such release position. 110 115 120

5. In combination, a car coupler having a locking dog adapted to be driven from a locking position to a release position by an element on an opposed car coupler during the act of coupling, an electric coupler fixed to the car coupler, a door for the electric coupler movable between closing and idle positions, an arm connected to said dog to be swung thereby as the dog moves from one of its positions to the other, and door operating 125 130

- means including an element having a lug projecting into the path of said arm, the parts being so constructed that said arm engages the lug and drives said element to open the door during the first part of the movement of the dog toward its release position and thereafter serves as an abutment engaged by the lug and holding the door open during the remainder of the travel of the dog to the release position.
6. In combination, a car coupler having a locking dog and an operating device for said dog, an electric coupler mounted on the car coupler, a door for said electric coupler, and door operating means connected to and between the door and said device.
7. In combination, a car coupler having a locking dog and means including a manually-actuated handle for operating said dog, an electric coupler mounted on the car coupler and having a door, and operating means for said door associated with said handle.
8. In combination, a car coupler having a movable locking dog adapted to be shifted by a part on an opposed coupler in the act of coupling, an electric coupler mounted on the car coupler and having a door, and means actuated by the shifting dog to open said door.
30. 9. In combination, an automatic car coupler having a part entirely in rear of the front face of the coupler that is shifted in the act of coupling, an electric coupler having a door, and means associated with said part to cause the said door to open upon the shifting of said part.
10. In combination, an automatic car coupler, an electric coupler mounted on the car coupler and having a door, and operating means for the door lying entirely in rear of the front face of the car coupler and including an element adapted to be engaged by a portion of an opposed car coupler and moved thereby in the act of coupling.
45. 11. In combination, an automatic car coupler, an electric coupler mounted thereon and having a door, and door-operating means operatively associated with a car coupler element for actuation thereby.
50. 12. In combination, a car coupler having an element that is shifted in the acts of coupling and uncoupling, an electric coupler mounted on the car coupler and having a door, a spring tending constantly to close the door, and means associated with said element to open the door against the resistance of the spring.
65. 13. In combination, a car coupler having an element that is shifted in the acts of coupling and uncoupling, an electric coupler mounted on the car coupler and having a door, a spring tending constantly to close the door, door-opening means including a member lying in the path of said element, said member and said element being so shaped that during the first part of the movement of said element in

the direction to open the door it drives said member ahead of it and during a considerable remaining portion of such movement acts simply as a lock to hold said member against backward movement.

14. In combination, coupling apparatus including a casing having contacts normally projecting beyond the front of the same in position to engage with similar contacts on a cooperating coupling apparatus, a door arranged in front of and having wings extending rearwardly past the sides of the casing, pivotal connections between the rear ends of the wings and the casing, and means associated with the coupling apparatus and set in motion by a companion coupling apparatus to cause the door to be swung down into an idle position upon the approach of a cooperating coupling apparatus and while the coupling apparatuses are still a considerable distance apart.

In testimony whereof, I sign this specification.
